UNITED STATES PATENT OFFICE

2,651,117

MOLDED PLASTIC SHOE FOR DOLLS

Josephine A. Harris, Creswell, Oreg.

Application August 28, 1951, Serial No. 244,011

1 Claim. (Cl. 36—2.5)

1

This invention relates to doll shoes, and more particularly to shoes of dolls that may be easily constructed of plastic materials.

It is an object of this invention to provide a doll shoe having an attractive appearance.

It is a further object of this invention to provide a construction whereby shoes for dolls may be easily and cheaply made.

It is a still further object of this invention to provide a doll shoe of such simplicity that it is adaptable to the manipulations of children in their play.

Other objects and advantages of the present invention will appear from the following specification and the drawing.

In the drawing.

Fig. 1 is a perspective view of a shoe embodying the present invention;

Fig. 2 is a perspective view of the shoe partially disassembled;

Fig. 3 is a side elevation of the foot-engaging or innersole portion of the shoe;

Fig. 4 is a bottom plan view of the foot-engaging or insole portion of the shoe;

Fig. 5 is a plan view of the strap which forms the heel and ankle-engaging portions of the shoe; and

Fig. 6 is a plan view of the vamp strap of the shoe.

Referring to the drawing, a shoe is shown having a ground-engaging bottom section 10, a foot-engaging top section or insole 11, a vamp strap 12 and a heel-and-ankle strap 13. The bottom section 10 comprises a heel portion 14, a shank portion 15 and a sole portion 16. The bottom section 10 is conveniently molded from a plastic material to form the hollow configuration best pictured in Fig. 2. As shown therein, a pair of laterally extending ribs, including a rib 17 in the vicinity of the ball line of the shoe and a rib 18 in the vicinity of the heel breast line of the shoe, are molded integrally in the bottom section 10. A pair of peg-receiving sockets 19 are formed in the top surface of rib 17 and a pair of peg-receiving sockets 20 are formed in the top surface of rib 18. The top edge 21 of the bottom section 10 intercepts a plane slanting generally from the heel to the toe of the shoe.

The foot-engaging top section or insole portion 11 of the shoe is also conveniently molded of plastic and is a substantially flat piece having a smooth upper surface 25. A laterally extending groove 26 is formed in the bottom surface of the insole in the vicinity of the ball line of the shoe. A second, laterally extending groove 27

2

is formed in the bottom surface of the shoe in the vicinity of the heel breast line. Transversely centered in groove 26 are a pair of pegs 30, and transversely centered in groove 27 are a pair of pegs 31. The edge of the insole is formed with a projecting lip 32 about the periphery, the lip having notches 28 therein at the ends of groove 26 and notches 29 at the ends of groove 27.

The design of the heel-and-ankle strap 13 and the vamp strap 12 is such that both pieces may be cut from a flat piece of material such as flexible, sheet plastic. As shown in Fig. 5, the heel-and-ankle strap 13 comprises a heel-engaging portion 36 from which project strap portions 37 which serve to engage the ankle of the foot. Depending from these first two portions which form a substantially continuous strip are a pair of depending straps 38 having a width substantially the same as groove 27. Holes 39 are punched near the ends of the ankle-engaging straps 37, and holes 40 are punched near the ends of the depending straps 38. The vamp strap as pictured in Fig. 6 is a long, narrow strap having a pair of holes 43 in the central portion thereof and holes 44 near the ends thereof. The central portion of the vamp strap 12 has a width substantially the same as the width of the groove 26.

The shoe is assembled by placing the central portion of the vamp strap 12 in the forward groove 26 as shown in Fig. 2, with the pegs 30 engaging the holes 43. The vamp strap is bent upwardly at the ends of the grooves to lie within the notches 28. The heel-and-ankle strap 13 is assembled on the shoe by bending the ankle-engaging portions 37 toward each other and then bending the depending straps 38 inwardly toward each other so that the bottom ends thereof abut each other. The ends are then inserted in the grooves 27, as shown in Fig. 2, with the pegs 31 engaging the holes 40. The upwardly projecting portions of the depending straps 38 pass through the notches 29 in the lip 32.

After the strap members have been engaged in the respective grooves, the entire top assembly is placed upon the bottom portion 10 of the shoe. The pegs 31 are engaged in the sockets 20 and the pegs 30 are engaged in the sockets 19. The lip 32 engages the top edge 21 of the bottom section 10, and the bottom section 10 may be permanently secured to the top section 11 by suitable means such as an adhesive material applied between the edge 21 and the lip 32.

The shoe may be secured to the foot by passing a ribbon 45 through the holes 39 in the ankle

strap and passing another ribbon 46 through the holes 44 in the vamp strap, as shown in Fig. 1.

The configurations of the bottom section and the top section of the shoe are relatively simple and, as observed previously, the respective parts can be readily molded from a thermoplastic or thermosetting plastic material. The parts making up the shoe are readily assembled, and an attractive shoe can be formed by suitable selections of colored plastic materials available for such purposes.

Modifications of the present invention should be readily apparent to those skilled in the art and it is to be understood that the form of my invention, herewith shown and described, is to be taken as a preferred example of the same, and that various changes in the shape, size and arrangement of parts may be resorted to, without departing from the spirit of my invention or the scope of the subjoined claim.

I claim:

A doll shoe comprising a hollow, open top, bottom section, an insole section having a substantially planar lower surface having an upstanding, peripheral wall entirely around it, the peripheral edge of said insole section and the upper peripheral edge of said bottom section mating cooperatively along substantially the entire extent of said edges, and said insole having a lower layer set back from said peripheral edge and fitting 30 closely the inside face of said peripheral wall, said insole section having a first laterally extending groove in said lower surface along the heel breast line and a first row of laterally spaced apart pegs depending downwardly therefrom and transversely centered in said first groove, said insole section having a second laterally extending groove in said lower surface in the vicinity of the ball line and a second row of laterally spaced apart pegs depending downwardly therefrom and transversely centered in said second

groove, the peripheral edge of said top section being notched inwardly at the ends of each of said grooves, said bottom section having a first laterally extending rib positioned beneath said first groove and having cooperative peg receiving sockets therein in which the pegs of said first row are received, and a second laterally extending rib positioned beneath said second groove and having cooperative peg receiving sockets therein in which the pegs of said second row are received, an ankle strap including portions passing through the notches at the ends of said first groove and lying within said first groove, said ankle strap portions having openings in which the pegs of said first row are engaged, a vamp strap including a portion passing through the notches at the ends of said second groove and lying within said second groove, said vamp strap portion having cooperative openings in which the pegs of said second row are engaged, the surface of said ribs being spaced from the surface of the corresponding groove by a distance no less than the thickness of the corresponding strap to permit reception of the corresponding strap portion therebetween, and means uniting said insole section to said bottom section along said mating edges thereof.

JOSEPHINE A. HARRIS.
